UNITED STATES PATENT OFFICE

ADOLPH A. THOMAS, OF NEW YORK, N. Y.

SELF-SEALING CAP FOR CONTAINERS

Application filed September 11, 1930. Serial No. 481,200.

This invention relates to receptacles of the type having a removable closure, and its object is to provide a self-sealing cap or cover of novel structure and improved operation. The basic feature of my new cap is an elastic flexible diaphragm or membrane which is automatically tensioned and forced into pressure contact with the top rim of the receptacle when the cap is tightened. This 10 sure contact between the receptacle and the tensioned flexible diaphragm of the cap produces a sealed joint.

My new cap is characterized by simplicity of structure and consequent cheapness of manufacture. There are no loose or removable parts, and no rubber gasket is required, as in prior caps. The practical advantages and novel features of my invention will be apparent from a description of the accompanying drawings, in which—

Fig. 1 shows a preferred form of my self-sealing cap, this view being in diametric section;

Fig. 2 is a sectional view of a container provided with the cap of Fig. 1;

Fig. 3 is a fragmentary view showing the locking ribs on the container of Fig. 2;

Fig. 4 illustrates a one-piece cap embodying my invention, this view being partly 30 sectioned for clearness; and

Fig. 5 shows the cap of Fig. 4 in sealing position on a container.

Referring to Figs. 1 and 2, the cap structure comprises a top member 10, a cylindrical shell or body portion 12, and an elastic flexible diaphragm or membrane 13. The top member 10 is formed with a cylindrical flange 14 and a peripheral recess 15. The shell 12 has a flange 16 adapted to fit over the flange 14 of top member 10, and the diaphragm 13 is rigidly clamped between flanges 14 and 16. In assembling the parts, the diaphragm 13 is placed over the flange 14 of member 10, and the part 12 is then driven home 40 over the flange in a tight frictional fit. During this operation the peripheral portion 17 of the diaphragm is bent into the cylindrical space between flanges 14 and 16, which securely holds the diaphragm in tensioned condition. After the parts are thus assembled,

the projecting portion 18 of the outer flange 16 is bent over into the peripheral recess 15 of top member 10. The dotted outline 18' in Fig. 1 indicates the normal position of the projecting portion 18 of flange 16. 55

The assembling of parts 10, 12 and 13 of the cap structure may be accomplished by machinery in a single operation. The shell 12 is preferably formed with a shoulder 19, which not only limits the relative inward movement of the shell and top member 10 during the assembling of the parts, but also cooperates with ring 15 to lock the parts against axial slipping. The top member 10 and shell 12 are preferably made of spun sheet metal 60 like aluminum or an aluminum alloy, brass, steel, and others that may be found suitable. It is also possible to make the cap members 10 and 12 of molded material of the type represented by formaldehyde condensation products, of which bakelite is probably the most familiar. In that case, the parts 10 and 12 would be molded as a single member and the diaphragm 13 would be embedded at its periphery in the plastic material during the 65 molding operation. This will be understood without additional illustration. The top member 10 protects the thin flexible diaphragm 13 against injury, and the intervening space 10' is sealed, so that no liquid can 70 get into it. 75

The diaphragm 13 is an elastic membrane sufficiently thin to be flexible and placed under tension when the cap is mounted on a container, as I shall presently explain. The diaphragm 13 is preferably made of spring metal, like steel, brass, nickel, phosphor bronze, duralumin, or other aluminum alloy, but it may also consist of non-metallic elastic material like bakelite, celluloid, waterproof or metallized fabric, india rubber, and perhaps others. If the cap is used on receptacles containing liquid or food products, the outer surface of diaphragm 13 should be plated or otherwise covered with a suitable 85 substance not affected by the contents of the receptacle. For example, if the diaphragm 13 is a disk of thin steel, it may be plated with chromium, which is impervious to atmospheric conditions and does not contami- 90 95 100

nate foods and liquids. If the diaphragm 13 consists of a thin elastic sheet of bakelite or similar material, no special coating will usually be necessary. It will be understood 5 that the foregoing enumeration of materials for diaphragm 13 is not intended as a restriction or limitation of my invention, but is merely for the purpose of illustration.

The container 20 in Fig. 2 terminates in an 10 extension 21 of considerably smaller diameter than the body of the container. When the cap is placed in sealing position on the receptacle, the top rim 22 thereof engages the diaphragm 13 along a circular line 13' 15 and the outer annular section 13a of the diaphragm is flexed or pulled down into slightly frusto-conical shape, whereby the central section of the diaphragm is stretched and forced into pressure engagement with the 20 rim. This pressure engagement produces a sealed joint along the circular contact line 13'. It is understood, of course, that the rim 22 is sufficiently smooth to make a fluid-tight joint with the tensioned diaphragm, which 25 automatically accommodates itself to any minute irregularities in the top surface of the rim.

In the basic aspect of my invention, any 30 practical means may be employed for removably locking the cap in sealing position on the container. In Figs. 1 and 2, the cylindrical shell of the cap is formed with inclined slots or grooves 23 adapted to receive the correspondingly arranged lugs or 35 projections 24 on container 20. In other words, the co-operating parts 23 and 24 constitute screw-threads or bayonet joints for locking the cap on the container by a rotary movement. The projecting flange 16 of the cap 40 may be roughened or knurled to afford a firm finger grip in turning the cap on and off. Instead of a screw connection between cap and container, I may use a hinged connection of any suitable type. It is immaterial how 45 the cover is locked in sealing position on the receptacle, provided that the diaphragm 13 is automatically tensioned and flexed to produce a sealed joint. In some instances an absolutely fluid-tight joint may not be required, 50 and I therefore use the expression "sealed joint" in a practical rather than strictly technical sense.

In the modification of Figs. 4 and 5, the cap is made of a single piece of sheet material 55 comprising a body portion or shell 25 and a diaphragm or membrane 26, which closes one end of the shell. The most practical way of making this one-piece cap is by spinning or otherwise shaping a sheet of elastic metal 60 into the required form, but I may also mold the cap as a single piece of bakelite, celluloid and similar material. The shell 25 is formed with screwthreads 27 adapted to engage the screwthreaded neck 28 of a suitable container 65 29, which is shown for illustration as a glass

jar, such as would be used for preserving fruit and the like. The jar 29 terminates in an extension 30 of reduced diameter. When the cap is screwed home on the jar, the rim of extension 30 engages the diaphragm 26 along a circular line 26' and causes the diaphragm to be flexed downwardly at the annular section 26a. This flexing of the elastic diaphragm forces the same into firm pressure engagement with the top of the jar, so that a sealed 70 joint is formed along the circular line 26'. What has been said about the materials suitable for diaphragm 13 applies to diaphragm 26.

It will be observed that the elastic sealing 80 diaphragm is normally flat (or substantially so) like a stretched membrane, and when the cap is loosened, the flexed diaphragm automatically springs back to normal position. In Figs. 1 and 2 the separate diaphragm 13 is automatically tensioned during the assembling of the parts, while in Figs. 4 and 5 the integral diaphragm 26 receives its normal tension in the spinning or shaping operation. If an underpressure develops in the container 85 after the cap is in sealing position, the tendency of the stretched diaphragm will be to curve inwardly, as indicated roughly at 26b in Fig. 5, and the effect of this inward buckling of the diaphragm is to increase the pressure along the contact edge 26'. The same applies to diaphragm 13 in Fig. 2. It is not necessary that the diaphragm shall actually buckle inwardly, for in some instances there 90 may only be a tendency of the diaphragm to do so, but even such tendency would improve the sealing of the container. The one-piece cap of Figs. 4 and 5 can be made so cheap that it is particularly adapted for household fruit jars and for containers intended to be 95 thrown away after the contents have been removed. Instead of making the diaphragms 100 13 and 26 of metal covered with a permanent plating that is not affected by the contents of the receptacles, the diaphragms can be left unplated and a lining of oiled or waxed paper (and the like) interposed between the diaphragm and the rim of the container. When I therefore speak of the diaphragm being in pressure contact with the 105 rim of the receptacle, I do not necessarily mean a direct contact between the two, but I 110 also include the possibility of an interposed lining.

It will be seen from the foregoing description that I have produced a self-sealing cap of unusually simple construction, which has no loose or replaceable parts and which can be made for any size, style or shape of container. For example, my new cap may be attached to cans or jars intended to hold tobacco, coffee, tea, sugar, flour, and other commodities used in the home. The cap is easy 120 to keep clean, since there are no crevices where particles of food or liquid can lodge. 125 130

- The sealing diaphragm 13 or 26 may vary in size from an inch or so to several inches, and even more than one foot. In fact, the larger the diaphragm, the greater will be its flexibility to establish a fluid-tight joint. The thickness and degree of flexibility of the diaphragm will naturally vary with different materials and in different sizes of cap, and those factors can readily be determined by experiment for each particular design of cap. Also, the width of the flexed portion 13a or 26a of the diaphragm will largely depend upon the normal diameter and tension of the diaphragm. The sealing effect of the cap increases with use, because the rounded rim of the container tends to wear a groove along the contact line of the diaphragm, and this groove acts like a seat for the contacting surface of the container rim. I do not mean to suggest by the last statement that the diaphragm soon wears out, for it goes without saying that it is made of wear-resisting material that will last as long as the container itself.
- Although I have shown and described certain specific constructions, my invention is not limited to the details set forth. Changes and modifications may be made without departing from the scope of the appended claims.
- I claim as my invention:
1. A self-sealing cap for containers, comprising a cylindrical body member for engagement over the neck of a container, a top member, and an elastic diaphragm held within said body member in spaced relation to said top member for sealing contact with the edge of the mouth portion of a container when the cap is engaged thereon.
  2. A closure for containers comprising a cylindrical shell for engagement over the neck of the container, a top member attached to said shell and closing one end thereof, and an elastic diaphragm marginally secured within said shell by said top member with the central portions of the top member and the diaphragm disposed in spaced relation, said diaphragm being disposed for engagement with the mouth edge of the container neck when the shell is engaged over the container neck.
  3. A closure for containers comprising a hollow body member for engagement over the neck of the container and a top member, an elastic diaphragm disposed within said body member with its central portion in spaced relation to said top member and marginally secured between portions of said body member and said top member for engagement with the mouth edge of the container neck when the body member is engaged over the container neck.
  4. A closure for containers comprising a cylindrical shell for engagement over the neck of the container, a top member attached
- to said shell by a circular overlapping joint, and an elastic diaphragm disposed within said shell with its central portion in spaced relation to said top member and marginally secured to the closure by said joint, said diaphragm being disposed for engagement with the mouth edge of the container neck when the shell is engaged over the container neck. 70
5. A self-sealing cap comprising a top member provided with a peripheral flange, a cylindrical shell attached to said cap, and an elastic flexible diaphragm rigidly clamped in tensioned condition between said flange and shell, said flange holding the tensioned diaphragm spaced from said top member to permit flexing of the diaphragm when the cap is mounted in sealing position on a container. 75
6. A self-sealing cap comprising a top member provided with a peripheral flange, a cylindrical shell attached to said cap, an elastic flexible diaphragm rigidly clamped in tensioned condition between said flange and shell, said flange holding the tensioned diaphragm spaced from said top member to permit flexing of the diaphragm when the cap is mounted in sealing position on a container, and a shoulder formed on said shell to limit the relative inward movement of the shell and top member. 80
7. The combination of a container having a cylindrical exteriorly screwthreaded portion near the top, an extension of reduced diameter above said screwthreaded portion, a cap having a cylindrical shell engaging said screwthreaded portion to secure the cap removably on the container, and an elastic flexible diaphragm carried by said shell to be drawn into pressure contact with the rim of said extension inwardly of the margin of the diaphragm by threading of the shell onto the screwthreaded portion of the container, whereby the diaphragm is caused to be tensioned and flexed over said rim into sealing contact therewith. 85
8. The combination of a container having a cylindrical exteriorly screwthreaded portion near the top, an extension of reduced diameter above said screwthreaded portion, a one-piece cap having a cylindrical shell engaging said screwthreaded portion to lock the cap removably on the container, and an elastic flexible diaphragm formed integral with said shell to be drawn into pressure contact with the rim of said extension inwardly of the margin of the diaphragm by threading of the shell onto the screwthreaded portion of the container, whereby the diaphragm is caused to be radially tensioned and flexed over said rim into sealing contact therewith. 90
9. A self-sealing cap comprising a top member provided with an integral cylindrical flange at the periphery, the top of said flange being sunk relatively to the main portion of said top member to provide an annular re- 125

cess, a cylindrical shell driven over said flange in a tight frictional fit, the outer peripheral edge of said shell being bent over into said annular recess, and an elastic flexible dia-
5 phragm rigidly clamped between said shell and flange, whereby said three parts are permanently connected to form a unitary cap structure in which said diaphragm is adapted to be tensioned and flexed into sealing contact
10 with a container.

10. In combination, a container inclusive of a neck or body portion and a mouth portion of less diameter than said neck or body portion forming an upward continuation of
15 the latter, a closure inclusive of a cylindrical portion to fit over the neck or body portion of said container, a flexible and elastic dia- phragm carried by said cylindrical portion for sealing contact with the edge of the mouth
20 portion of the container, and means for draw- ing the closure downward over the body portion of the container thereby to draw the dia- phragm into sealing contact with the mouth edge of the container and to radially tension
25 the diaphragm.

11. A self-sealing closure for containers comprising an elastic membrane adapted to be engaged against the edge of the mouth of the container, said membrane being of greater
30 diameter than the mouth edge of the container and being formed of material suffi- ciently thin and elastic to be marginally flexed downward outwardly of its circular line of contact with the mouth edge of the container
35 and to thereby have its central portion tensioned thus to form a tight seal of the mem- brane against the mouth edge of the container, and means for marginally drawing the mem- brane downward and for radially tensioning
40 the same when the membrane is engaged against the mouth edge of the container.

ADOLPH A. THOMAS.
